UNITED STATES PATENT OFFICE.

CHRISTIAN HIERING AND ALBERT FULLER, OF NEWARK, NEW JERSEY,
ASSIGNORS TO THE J. E. MERGOTT COMPANY, OF NEWARK, NEW JERSEY,
A CORPORATION OF NEW JERSEY.

BAG-FRAME.

No. 851,421.

Specification of Letters Patent.

Patented April 23, 1907.

Application filed April 6, 1906. Serial No. 310,205.

To all whom it may concern:

Be it known that we, CHRISTIAN HIERING and ALBERT FULLER, citizens of the United States, residing in the city of Newark, in the county of Essex and State of New Jersey, have invented certain new and useful Improvements in Bag-Frames; and we hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to improvements in bag frames and has for its object, an improved method of securing the body of the bag, that is, the leather or fabric of which the body is formed to the hinged bag frame proper.

Hitherto, it has been customary in the construction of bag frames to provide channeled sections into which the margin of the open part of the bag body is secured by means of filling plates held in position by means of rivets. Structures of this character are not only expensive to manufacture, but open to the objection that they are less rigid and more liable to distortion in actual use.

Our present invention aims to overcome these difficulties while at the same time a very rigid and substantial frame composed of a minimum number of parts and firmly securing the bag body to the frame proper, is provided.

In carrying out our invention, we make use of the structure illustrated in the accompanying drawings, in which:

Figure 1 is a side view of a bag frame, partly in section, showing the bag body in position. Fig. 2 is an enlarged cross-section on line x of Fig. 1. Fig. 3 illustrates a perspective enlarged view of the marginal clip. Fig. 4 illustrates a cross-section of a modification showing the bag frame and clips in position, and Fig. 5 illustrates in cross-section, still another modification of the bag frame.

Similar letters of reference refer to like parts throughout the specification and drawings.

The bag frame A is composed of the two hinged sections a , a , substantially P-shaped in cross-section, with the convex portion a' and the plane portion a^2 separated at the middle of the plane portion, and forming the hollow channels for the reception of the margins of the bag body as illustrated in Figs. 2 and 4. The bag body itself is cut to the shape of the members a , a and has along its margin, the clips B of general cylindrical shape with the serrated gripping edges secured to its edges b at intervals throughout its length as illustrated in Fig. 1. In assembling the bag frame and body, the convex portions of the frame members A are left open as indicated in full lines in Fig. 5; the channeled openings being of sufficient width to receive the margins of the bag body C, with the clips B in position, after which the convex portion of the members are pressed down upon the plane portions of the members so as to grip the margins of the bag body C with the clips B in the hollow portions of the bag frame members as illustrated in Fig. 2. In this way, the bag body is held firmly secured to the frame members without any liability to separate. The clips B, when gripped to the margin of the bag body serve as a bead along the margin, and when the frame is compressed into the shape illustrated in Fig. 2, the clips B lock the bag body to the frame.

In the modification illustrated in Fig. 4, we have shown the frame members of substantially the same cross-section as in Fig. 2, but the members themselves are reversed, that is, the convex portions a' , a' of the members are in contact when the bag is closed instead of the plain flat sides a^2 , a^2 of the members as in Fig. 2. In this modification, we have also shown beaded indentations a^3 , along the plain or skirted sides of the bag frames. They serve as an additional gripping means in conjunction with the edge a^4 of the convex portion, for more firmly gripping the margins of the body with the clips B enclosed as shown. It should be understood in this connection that the indented bead a^3 may be applied to the other modifications for the same purpose.

In Fig. 5, we have shown a slight modification of the cross-section of the bag frame member, for the purpose of providing a flat

upper face a^5 , which in some cases forms a more convenient surface for the attachment of the different kinds of means and also for the attachment of handle caps. The general purpose and function, however, of the semi-cylindrical portion a' is the same and when bent into the position indicated in dotted lines will grip the margins of the bag body with their clips B in the same manner as that indicated in connection with Fig. 2.

It will thus be seen that we have provided a novel and serviceable means for securing the bag frame to the body in such a way as to accomplish fully the results sought for, namely, that of firmly securing the bag body to the bag frame without the liability of their accidental separation in ordinary or reasonable use.

We claim:

1. A hand bag comprising hinged members provided with hollow channels, a bag body, and clips secured to the margin of said bag body, said margin and clips being inserted within the channels of the hinged members and secured therein by closing the channeled openings of said members.

2. A hand bag comprising hinged members provided with hollow channeled openings a bag body having metal clips secured to its margins, said bag body being secured within said channeled openings by closing the same over said clips.

3. A hand bag comprising a bag body having a series of metallic clips secured to its margins to form marginal beads, hinged frame members having hollow channels therein comprising a plane portion and a concave portion, the margins of the body being inserted within said channels which are closed over said clips and gripped to the said margins of the bag body.

4. A hand bag comprising a bag body and a pair of channelled hinged frame members, a series of metal clips secured to the margins of the body opening, said margins being secured within the channels of said frame members by compressing the edges of said channels together over the marginal clips of the bag body.

5. A bag frame member comprising a metallic strip bent to form an open or channelled groove, substantially semi-cylindrical in cross-section with the edge of the plane side extending below the edge of the curved side.

6. A bag frame member composed of a channelled metal strip semi-cylindrical in cross-section, the plane side of said strip extending below the curved side, the edge of said curved side being directed towards said plane side to form a gripping means for securing the edge of the bag body in position.

7. A bag frame member having a plane portion and a concave portion forming a hollow open channel throughout the length of the member, said open channel being adapted to close upon and grip the margin of a bag body and a beaded indentation running the entire length of the plane portion adjacent to the open edge of the concave portion.

8. A bag frame member having a plane portion and a concave portion united to form an open channel, said concave portion being united to said plane portion by a flat face portion lying at right angles to said first named plane portion.

This specification signed and witnessed this 4th day of April 1906.
